UNITED STATES PATENT OFFICE.

WILLIAM H. HARVEY, OF WATER VALLEY, MISSISSIPPI.

CASING SPEAR.

Application filed April 6, 1927. Serial No. 181,550.

My present invention relates generally to devices for pulling casing or pipe from water, oil or gas wells, and more particularly to that class of pipe pulling and adjusting devices commonly known as casing spears, my primary object being the provision of a casing spear which cannot become jammed while in operation and which can be released and re-engaged in a well 10 without drawing the tool to the surface.

A still further object is the provision of a tool having a pipe gripping element and means whereby such element may be jarred both in upward and downward directions 15 and which is generally more effective and efficient in use than those now employed.

In the accompanying drawing which illustrates my present invention and forms a part of this specification,

20 Fig. 1 is a side elevation of my improved casing spear;

Fig. 2 is a side view, partly in elevation and partly in section thereof taken on line 2—2 of Fig. 1;

25 Fig. 3 is an enlarged vertical longitudinal section through a portion thereof;

Fig. 4 is a horizontal section taken on line 4—4 of Fig. 1; and

30 Fig. 5 is a detail perspective view of the sliding sleeve.

Referring now to these figures, my invention proposes a casing spear consisting of a barrel 10 having upper and lower heads 11 and 12 which form hammers in use. The 35 heads 11 and 12 are preferably threaded on the barrel ends as shown and also pinned thereto by transverse pins 13 and the upper head is also preferably provided with an upstanding threaded extension 14 providing 40 for the coupling of the barrel to a drill stem or drill line or line of pipe by means of which the spear is suspended and manipulated.

The lower head 12 preferably has a 45 pending threaded extension 15 for the connection and support of a guide bit 16 through a bit collar 17, the bit operating in use to guide the spear into a pipe and to clear out any obstructions which it may be 50 necessary to remove in permitting the spear, as a whole, to function. This bit may have openings 18 permitting the passage of water or fluid downwardly through the same from the barrel and supplied to the 55 latter through the drill stem or line.

The upper and lower heads 11 and 12 are

also provided with circumferentially spaced arms 19 and 20 projecting toward one another and also spaced from the barrel 10, these arms constituting hammers or jars 60 for a purpose which will presently appear.

Loosely disposed on the barrel 10 between the heads 11 and 12 is a sliding sleeve 21 having at spaced points therearound longitudinally movable casing-engaging slips 22 65 provided with surface teeth and side ribs 23 which are disposed in slanting guide slots 24 of the sleeve. The teeth of these slips are inclined in an upward direction and the slots 24 are inclined so that the slips move 70 radially of the sleeve in an outward direction when shifted downwardly.

The sleeve 21 also has upper and lower grooves 25 and 26 which the hammer arms 19 and 20 are adapted to enter, these grooves 75 being alined with the slips 22 so that the arms may thus engage the upper and lower ends of the slips. Between the grooves 25 and 26, the sleeve has surface springs 27 secured at their ends to the sleeve and so 80 arranged as to frictionally engage the inner surface of a casing and thus hold the sleeve in place so that the barrel can be shifted therethrough both longitudinally and rotatively.

Thus when the spear is lowered into a casing, the sleeve becomes frictionally engaged therewith and the barrel can then be turned so that its upper hammer arms 19 will enter the upper grooves 25 of the sleeve 90 when the barrel is lowered, thus jarring or hammering the slips 22 downwardly and outwardly upon the sleeve into gripping relation with the inner surface of the casing. Then before the barrel is raised, it is turned 95 slightly so that the lower hammer arms will, in its upward movement, engage the lower end of the sleeve between the lower grooves and thus bear against the body of the gripped sleeve.

When it is desired to release the sleeve so that the spear can be either removed from the well or shifted to grip the casing at another point, the barrel may be turned in the sleeve and shifted downwardly and its upper arms 19 will engage the upper end of the sleeve between the grooves 25, thus breaking the grip of the slips and the barrel again turned and shifted upwardly with its lower arms 20 alined with the lower 110 grooves 26 of the sleeve so that these arms will thus engage the lower ends of the slips

when the spear is elevated from the casing.

By thus providing for hammering or jarring the sleeve and slips from both above and below, my invention broadly proposes an improved arrangement which will avoid all danger of jamming and will permit of better control of the operation as well as greater ease in its accomplishment.

Furthermore, after engagement of the slips with a pipe as previously described, hammering of the upper arms downwardly against the upper ends of the slips enables the operator to jar the pipe downwardly, while hammering of the lower arms upwardly against the lower surface of the sleeve enables the operator to jar the pipe upwardly.

I claim:

1. A casing spear including a sleeve, slips movable thereon to grip a casing, a barrel 20 movable through the sleeve, and heads on the barrel above and below the sleeve having arms projecting toward one another, said barrel being turnable to shift the said arms into and out of alinement with said slips.

2. A casing spear including a barrel having upper and lower heads, a sleeve loosely mounted on the barrel between said heads, and slips movable on the sleeve to grip a 30 casing, said heads having means shiftable with the barrel to engage both ends of the sleeve and to engage both ends of the slips independent of the sleeve.

3. A casing spear including a barrel having upper and lower heads, a sleeve loosely mounted on the barrel between said heads, and slips movable on the sleeve to grip a casing, said heads having means shiftable with the barrel to engage both ends of the sleeve and to engage both ends of the slips independent of the sleeve, and means also carried by the sleeve to frictionally engage a casing.

4. A casing spear including a sleeve, slips adjustable thereon to engage a casing, and a support for the sleeve having means to engage both ends of the sleeve and the said slips independently of one another.

5. A casing spear including a sleeve, slips 50 adjustable thereon to engage a casing, and a support for the sleeve having means to engage both ends of the sleeve and the said slips independently of one another, said means including a barrel movable through and rotatable within said sleeve.

6. A casing spear including a sleeve,

spaced apart slips adjustable thereon to grip a casing, a barrel slideable through and rotatable in said sleeve, upper and lower heads fixed on the sleeve, and arms extending toward one another from said heads to engage the ends of the sleeve, said sleeve having grooves alined with the slips to receive the said arms.

7. A casing spear including a sleeve, 60 spaced apart slips adjustable thereon to grip a casing, a barrel, heads fixed to the barrel above and below the sleeve, and arms spaced from one another on said heads for movement against the sleeve, said barrel 70 being shiftable through the sleeve and rotatable with respect thereto for shifting the said arms into and out of alinement with the slips.

8. In a well fishing tool, a barrel, a normally contracted expandable member slidably arranged on the barrel, and a head carried by each end of the barrel; one of which being engageable with the expandable member to expand the latter at will and the 80 other being also engageable with the expandable member to contact the same at will.

9. In a device of the character described a barrel, a sleeve slidably mounted thereon and having a plurality of longitudinal 85 spaced inclined grooves therein, object engaging slips longitudinally adjustable in the grooves whereby to move the former readily outwardly, or inwardly, a rotatable head upon each end of the barrel and provided with oppositely projecting spaced fingers, one of the heads being adapted to be positioned with its fingers in longitudinal alinement with the slips whereby upon reciprocation of the barrel the slips will be forced 95 downwardly in the grooves to gripping position, and the other head being adapted to be positioned with its fingers disposed in longitudinal alinement with the slips to force the latter to normal position when it is desired to release the object with which the device is engaged.

10. In combination a well tubing to be received in a well casing, a barrel attached to the lower end of the well tubing, a normally contracted expandable member slidably arranged on the barrel, and a head carried by each end of the barrel either of which being engageable with the expandable member to expand or contract the latter upon jarring 110 the well tube in a predetermined direction.

WILLIAM H. HARVEY.
